UNITED STATES PATENT OFFICE.

BERNARD J. POST, OF SAN FRANCISCO, CALIFORNIA.

ELEVATING-CUSPIDOR.

1,193,607.

Specification of Letters Patent. Patented Aug. 8, 1916.

Application filed January 3, 1914. Serial No. 810,230.

To all whom it may concern:

Be it known that I, BERNARD J. POST, a citizen of the United States, residing at San Francisco, in the county of San Francisco and State of California, have invented certain new and useful Improvements in Elevating-Cuspidors, of which the following is a specification.

The object of my invention is to provide means for elevating a cuspidor from a floor position to such close relation with respect to the user as to facilitate entrance of the expectorated matter into the cuspidor.

In the sick room, and likewise in hospitals, patients frequently expectorate on the floor by reason of the fact that they are not able to carefully dispose their heads immediately over the cuspidor. Also in hotels, very unhygienic conditions exist in the immediate vicinity of a spittoon where careless users expectorate upon the floor instead of into the spittoon.

A further object of my invention is to provide an elevating spittoon or cuspidor which is especially serviceable in connection with dental work where permanent proximity of a cuspidor near the arm of a dental chair would subject the more delicate patient to nausea, the device of my invention being especially advantageous in view of the fact that it can be almost instantly elevated into a position so that the patient being in the dental chair could expectorate without having the cuspidor in full view at all times.

Other features of novelty will be more fully described in connection with the accompanying drawings and will be more particularly pointed out and ascertained in and by the appended claims.

In the drawings, Figure 1 is a view in side elevation of one form of the device of my invention showing some of the electrical connections diagrammatically. Fig. 2 is a plan view thereof.

Like characters of reference designate similar parts throughout the different figures of the drawings.

As illustrated, 1 designates a floor line and 2 a wall of an apartment or corridor in which the device of my invention is shown disposed. In the wall 1 may provide any suitable form of baseboard plug structure 3 whereby conductors 4 and 5 may be connected with conductors 6 and 7, leading to a source of current.

I have shown the device of my invention embodied in a suitable base or platform 8 which may be mounted on wheels 9, if it is desired to move the same about. An upright 10 is mounted upon the platform or base 8 and may be of the height shown if the device is to be used in connection with a dental chair or other operating support, or it may be of reduced height if the device of my invention is disposed opposite a bed or chair of an ordinary construction. A cuspidor is indicated at 11 and may be provided with a bail 12 to which elevating cords 13 may be attached, as at 14. The cords 13 extend over pulleys 15 which are journaled upon arms 16 of a bracket 17 which is secured to the upright 10. The cords 13 are connected, as at 18, to a single cord 19 which is trained over a pulley 20. The pulley 20 is mounted in a bracket 21, secured to the upright 10 and provided with arms 22 on the terminal ends of which a roller 23 is journaled under which the cords 13 are trained. The cord 19 extends downwardly and is connected with a shaft 24 which may extend through the upright 10.

It will be readily seen that when the shaft 24 is rotated, it will wind the cord 19 thereabout and elevate the cuspidor 11.

The means for elevating the cuspidor as herein shown are of an electrical form although I do not wish to be limited to this particular construction.

I have shown an electrical motor 25, mounted upon the base 8 and directly connected to the shaft 24 so as to rotate the same.

One of the conductors, namely 5, leads to the motor 25, and therefrom at 26 said conductor leads to a terminal 27. Conductor 4 leads to the pivot 28 of a switch having a handle or actuating portion 29 and a circuit-closing head 30. From 28, a wire 31 leads to an incandescent lamp 32 which is carried adjacent the bail 12 so as to illuminate the area immediately above the cuspidor when the latter is used in a darkened room. Leading from lamp 32 is a conductor 33 which is connected with a terminal 34.

When the switch lever is in the position shown in full lines, the circuit will be open and the cuspidor 11 will maintain its position on the base 8 by gravity. When it is desired to elevate the cuspidor into convenient accessibility to permit the user to ex-

pectorate therein, the switch handle 29 will be moved into the dotted-line position so as to move the head 30 into circuit-closing position with respect to switch terminals 27 and 34. This will close circuit and start the motor and also cause the lamp 32 to glow. The motor will rotate shaft 24 and wind the cord 19 thereon thereby elevating the cupidor 11 until it reaches the dotted-line position shown in Fig. 1. Upward movement of the cupidor 11 above such position will move the switch 29 into the position shown in full lines so as to open circuit. This will stop the motor and the weight of the cupidor 11 will cause the same to descend again onto the base 8. There will be enough friction of the parts together with the drag imparted by even an armature of the small type of motor which I may use, so that the cupidor 11 will not descend too rapidly so as to objectionably crash upon the base 8. I may however, desire to place any form of yielding support on the base against which the impact of the cupidor 11 may be cushioned. A stop 35 may be provided to limit movement of the switch lever 29 in one direction.

It is believed that the advantages and utility of my invention will be clearly understood from the foregoing description and while I have herein shown and described one specific form of my invention, I do not wish to be limited thereto except for such limitations as the claims may import.

I claim:—

- 25 1. In combination, an expectorant receiver, means for moving the same toward the user, and means for illuminating an area adjacent the receiver, said means being operable by the elevation of the receiver to facilitate use of the same substantially as described.
- 40 2. In combination, an expectorant receiver, means for elevating the same toward the user, a device operated upon elevation of the receiver to a usable position for throwing out said means to permit descent by gravity of said receiver to an initial position.
- 45 3. In combination, an expectorant receiver, an upright, a driven shaft carried by the upright, a cord-like element connected with said receiver and shaft to be elevated by movement of said shaft, and means actu-

ated by the receiver for arresting movement of said shaft, substantially as described.

4. In combination, an expectorant receiver, an upright, a power-driven winding shaft, pulleys carried by said upright, a cord-like element connected with said receiver and with said shaft and trained about said pulleys, and means actuated by the receiver for arresting movement of said shaft, substantially as described. 55 60

5. In combination, an expectorant receiver, an electric motor provided with a shaft, a cord-like element connected with the receiver and with said shaft for elevation of the receiver to a usable position upon winding movement of said shaft, and a switch for said motor adapted to be actuated by the receiver to arrest elevating movement of the latter, substantially as described. 65 70

6. In combination, a base provided with an upright, an expectorant receiver on said base, a pulley carried by said upright, a cord connected with said receiver and trained about said pulley, an electric motor carried by said base and having a shaft for operation of the cord, a circuit including a motor and a switch for closing the circuit by the user to elevate the receiver, said switch being operable by the receiver to open the circuit upon elevation of the receiver to a predetermined height, substantially as described. 75 80

7. In combination, a base provided with an upright, an expectorant receiver on said base, a cord connected to said receiver, a motor shaft journaled in said upright and connected with said cord to operate the same and elevate said receiver, a motor for operating said shaft, a circuit including said motor and an electric switch for operation by the user to close said circuit and cause the motor to elevate said receiver, said switch being operable by the receiver to open said circuit upon elevation of the receiver to a predetermined height, substantially as described. 85 90 95

In testimony whereof I affix my signature in presence of two witnesses.

BERNARD J. POST.
